U.S. CL. D27—7

FIG. 1.

FIG. 2.

FIG. 3.

FIG. 4.

FIG. 5.

FIG. 6.

FIG. 1 is a top plan view of a combined cigarette holder and removable support showing my new design;

FIG. 2 is a left end elevational view;

FIG. 3 is a right end elevational view;

FIG. 4 is a side elevational view.

FIG. 5 is a longitudinal section as taken on the line 5—5 of FIG. 1; and

FIG. 6 is a transverse section as taken on the line 6—6 of FIG. 1.

The characteristic feature of my design resides in the configuration of the supporting ring in conjunction with the cigarette holder.

I claim:

The ornamental design for a combined cigarette holder and removable support, as shown and described.
